Anchor.

FERDINAND MARTIN, OF MARSEILLES, FRANCE.

Letters Patent No. 722, dated March 19, 1861. Patented in England, August 27, 1859.

SPECIFICATION.

TO ALL TO WHOM IT MAY CONCERN:

Be it known, that I, FERDINAND MARTIN, of Marseilles, in the French Empire, merchant, have invented "a new and improved method of forming and constructing Anchors;" and I hereby declare, that the following is a full and exact description thereof, and the drawings annexed hereto form a part of this specification, and are intended to illustrate it and render it clearly intelligible to any one acquainted with these matters.

My anchor is composed of three main pieces, and three or more subordinate parts; by the form, combination, and arrangement of which, I am enabled to obtain vastly greater holding power than can be had by any anchor I at present know; moreover, while it acts with unerring certainty, from its construction, it is not only more easily handled, but it avoids nearly all the inconveniences and defects of the present system of anchors.

The three main portions of my anchor consist of the shank, the head, and the arms, and the form, arrangement, combination, and action of these three parts constitute the peculiarity of my invention.

In the accompanying drawings, which are intended to illustrate my description of the form of these parts, as well as of the subordinate details, and also to show the arrangement, and the mode of combining one with another, and their action, when so combined as to form the anchor, I wish it understood, that I do not bind myself to the exact outline, shape, figure, dimensions, or details, as each of these may be varied and modified to suit particular applications, but I claim the main or governing principles of form of construction, and of combination, by which the action of the anchor, as hereinafter described, is obtained.

*Martin's Improved Anchor.**Description of the Drawings.*

Figures 1 and 1* are elevations of the shank.

Figure 2 is a side elevation of the head, showing the web portion *b*, the eye *b'*, the palms or flanges *b''* *b'''*, and the crown *b⁴*.

Figure 2* is an end view of the same, and

Figure 2*, a section of the same, on the line *x* *x'* of figures 2 and 2*.

Figure 3 is an elevation of the arm, or arms *c*, with their palms, or flukes *c'* *c''*.

Figure 3* is a section of the same, upon the line *y* *y'* of figure 3.

Figure A is an elevation of the anchor, composed of the previous mentioned parts and the hereafter mentioned subordinate details.

Figure B is a perspective view of the anchor, the arms and head being in a particular position, as hereinafter described. Figure C is also a perspective view of the anchor in a different position from the last.

Figures D E F are side elevations of the anchor, in different positions referred to in the description hereinafter. Figures 4 and 4*, 5 and 5*, 6 and 6*, 7 and 7*, are elevations and plans of the details connected with the anchor & referred to & described hereafter. Figure G is an elevation of the anchor, showing a modification of the form & mode of combining and arranging the main constituting parts, and differing somewhat from that shown in the previous figures, as will be hereafter described.

Figures 9 and 9*, 10 and 10*, show the form of the details uncombined.

Referring again to figures 1 and 1*, it will be seen that the shank at its upper end is shouldered off and terminates in two cheeks *a* *a*, which have an eye or aperture *a'* passing through each. Within the space between the two cheeks *a* *a*, the head *b* (fig. 2) is inserted and in such a manner, that the eye *b'* coincides with the eyes *a'* *a'* of the cheeks; each face of the web portion of the head being adjacent to one of the inner faces of the cheeks. The shank and head being so arranged, one of the fluked ends *c* of the arm is passed through the eyes of the cheeks, and the head is carried onwards until the arms take a central and symmetrical position about the shank; the fluked extremities being turned from the head, as shown in all the different figures. In this position they are firmly keyed to the head, so as to form an axis upon which, and with which it turns, or oscillates within the eyes of the cheeks. In order to allow this axial portion of the arm to oscillate freely and to diminish the friction, I introduce a bearing on the under side of each eye in the cheeks; figures 4 and 4* show the position of the bearing *d*, and the mode of placing and fixing it upon the cheeks.

Upon the crown of the head *b⁴*, I fix the "buoy shackle" *e*, (see figures 5 and 5*), and at the lower extremity of the shank *a²*, I attach the main chain shackle, (see figures 6 and 6*.) The mode of attaching these two shackles will be easily seen on comparing the figures with the points of attachment. In order to give a greater lateral steadiness, as well as to increase the holding power of the anchor, I fix to the shank, and in a plane parallel with its own, a curved, or straight arm *g* *g'*,

Martin's Improved Anchor.

(figures 7 and 7*); the mode of fixing this arm to the shank is by inserting it up to the shoulder g^2 , through the aperture a^3 of the shank; then keying it firmly to the latter.

Figure A is an elevation, showing the anchor, with all the before named parts in their positions; and ready to be applied.

Figure B is a perspective view, showing the position the anchor takes when thrown out, and lying on the ground; no holding force acting upon it.

Figure C is also a perspective view of the anchor, showing the position the arms take when about to enter the ground; a holding or pulling force being applied at the free end of the shank, from the main shackle.

The action of the anchor, when constructed of the before mentioned parts, is as follows: It will be evident from the previous description, and by reference to the drawings, that as the head turns upon a centre within the cheeks of the shank, it will vibrate in an arc, whose length will be proportional to the distance between the lower ends of each of its flanges; for the contact of either of these flanges with the shank stops the angle of vibration, or oscillation, hence by causing these to recede, or approach each other, the angle of oscillation will be increased or diminished; in like manner, since the arms are attached and oscillate with the head, they will describe with it an equal and similar angle; if, then, the shank be held in a fixed position, the head and arms will turn round it in an arc, as described; on the other hand, if the head and arms be held in a fixed position, the shank will move through a similar and equal angle. The dotted lines in figures 1, D and E, show the angles and arcs described by the head and arms with the shank, when the head has the form and dimensions shown in the drawings. The other figures of the anchor show the different positions also of the head, arms, and shank, in reference to each other. It will be at once seen then, that if force be applied to the free ends of the shank, at the main chain shackle, the first effect of this force will be to slightly elevate the free end of the shank; the direction of the force being such as would have a tendency to drag or pull the anchor forward. The position of the anchor, when on the ground, and about to be acted upon by such a force, is shown in figures B and D, the arrow indicating the direction of the force; this tendency of the anchor to move in the direction of the force is, however, arrested by the action of the points of the flukes entering into the ground; the moment this takes place, the arms, and with them the head, describe an arc round the points of the flukes as centres, and stand at the maximum angle with the shank, the free end of which buts against the ground, the lower portion of the elevated flange of the head bearing against the shank at the shoulder.

The relative positions of the various parts last described are shown in figures C and E. The arms or flukes are now in such a position, that, if the force be continued, they must enter the ground, and will sink farther and deeper, until they take the position shown in Figure D. It will be seen that in this anchor there are three points of resistance to the pulling force, namely, the resistance of the flukes of the arms, and that of the point of the free end of the shank; moreover, when

Martin's Improved Anchor.

the anchor gets embedded, as shown in figure F, a considerable amount of resistance is given both by the flange of the head and by the curved rod *g*.

Figures G, 8 and 8^a, 9 and 9^a, show a modification in the form of the parts, as well as in the arrangement, differing somewhat from the anchor, and the parts last described. In this case the shank is made shouldered off as before, but without having the cheeks formed on it; having, however, an eye in the shoulder part. The head on the contrary is composed of two parts, (see figures 9 and 9^a,) and bolted together, so as to have a hollow space between them; the upper part of the shank is inserted within this space, and the arms passed through as before; hence the only difference between the anchor so made, and the former described, being, that in the first, the head is inserted between the cheeks, while in the latter the shank is inserted between the sides forming the head.

The action of all the various parts of this anchor is the same as that last described herewithin.

I do not claim the invention of revolving or movable fluked anchors, for I am aware that they were invented many years ago.

My improvement presents the following advantages. First. Head: It not only performs the same functions, as in all other anchors of this class, viz.: limits the angle of rotation of the arms, but from its form it enters the ground and acts like a third fluke; thus adding greatly to the holding power of the anchor.

Second. Flukes: These are of an entirely new form, which the inventor calls the "sword form," and are the results of numerous experiments, involving all forms of flukes, and having the following advantages: *a*, they enter the ground quickly and easily, without disturbing or loosening the ground in front of them, which every other form does: through this action the solidity of the ground around the flukes being preserved, the holding power is largely increased; *b*, owing to the form of the flukes, the arm is made of one piece, without having the flukes welded on, which not only increases the strength, but lessens the cost of manufacture.

Third. The Arms: Their peculiar mode of attachment to the shank, together with the form of the flukes, permits the whole to be easily and quickly taken to pieces, which is not the case generally with other forms of this kind of anchor.

Fourth. The Steadying bar gives to the "flukes" an equal penetrating power, while at the same time by its own resistance to the ground in which it gets embedded, it increases the holding power; it also prevents the anchor from capsizing when the ship swings, and as in no case is the pulling force on the anchor ever exerted in the line of the axis of the shank, or perpendicularly to the resistance of the flukes, (although in theory it is always supposed to do so,) the action of the steadyng bar is such as to prevent the rotation or disengagement of one of the flukes, which necessarily happens with all other anchors of this kind.

Having thus described my invention, I claim, and desire to secure by Letters Patent, as an improved article of manufacture—

An anchor, provided with a curved steadyng bar, sword shaped flukes, grapping head or third fluke, and otherwise constructed as herein shown and described.

Martin's Improved Anchor.

In witness whereof, I, the said FERDINAND MARTIN, have to this specification appended my name, this twenty-sixth day of September, in the year one thousand eight hundred and fifty-nine, in the presence of,

FERDINAND MARTIN.
